UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR.

1,137,967.

Specification of Letters Patent.

Patented May 4, 1915

Application filed February 2, 1910. Serial No. 541,612.

To all whom it may concern:

Be it known that I, DAVID W. HAWKSWORTH, a citizen of the United States of America, residing at Detroit, in the county 5 of Wayne and State of Michigan, have invented certain new and useful Improvements in Cars, of which the following is a specification, reference being had therein to the accompanying drawings.

10 The invention relates particularly to freight cars, and has for its object a construction wherein the siding or sheathing may be removed in part or in its entirety for repair or replacement without disturbing 15 the roofing structure or fascia, thereby lessening the amount of labor and materially decreasing the cost of repair.

In the present day construction of freight cars, to repair or replace the siding it is 20 necessary in all instances to remove the fascia at least, and in many cases to remove or loosen a material part of the roof itself. This latter is particularly true in constructions where a metallic covering is employed, 25 and in these instances the loosening and bending of the metallic sheets is difficult and undesirable, as the bending has a tendency to crack and break the sheet.

These difficulties are obviated by a construction hereinafter described and illustrated in the drawings, in which:

Figure 1 is a sectional perspective view of a freight car, showing an outside metal roof construction; Fig. 2 is a side elevation thereof, partly broken away; and Fig. 3 is a sectional view, illustrating the application of my invention to an all-wood construction of roof.

In the drawings thus briefly described, A 40 represents the substructure, including the usual side plate of the freight car roof, B the fascia, C the metallic covering composed preferably of a plurality of sheets, and D the sheathing or car siding.

45 In the type of roof illustrated, the metallic sheets extend over the fascia, as shown, and are provided with down-turned marginal or eave portions E, which are nailed to the fascia side, as indicated.

To permit of the removal of the siding, a gain F is formed longitudinally in the lower portion of the fascia adjoining the side plate, and the siding or sheathing of the car is cut to a length to extend and to house at its upper edge within this gain, as indicated in Fig. 2, the gain exceeding in width the thickness of the sheathing to permit of its ready removal or replacement. The siding is held in place by nailing to the side plate in the ordinary manner, but the nails as shown are below the fascia so as to be readily removed without disturbing the fastia when it is desired to replace or repair the sheathing.

In the type of car wherein an all-wood roofing is employed, as shown in Fig. 3, the same detachable construction of siding may be employed, the fascia being preferably gained in this instance as in the preferred form shown in Figs. 1 and 2 of the metal roof construction. It will be understood, however, that while the gain is the preferable manner of providing the overhang that the fascia has over the siding to protect the joint at the top edge of the latter, various modifications may be employed without in any manner departing from the spirit of my invention. I do not desire, therefore, to be limited to the construction shown, nor to the specific applications of my invention.

From the foregoing description and illustration of the invention, the requirements for the removal of the sheathing or parts thereof will be obvious, it merely being necessary to withdraw the nails fastening the same in place, and subsequently removing the sheathing from beneath the fascia, and afterward inserting new boards in a similar manner, and this without in any way disturbing either the fascia or the roof structure, or necessitating any bending of the metal plates where a metallic covering forms a part of the roof.

What I claim as my invention is,—

In a freight car, the combination of a side plate, a fascia secured thereto, a roof connected to the fascia, and a sheathing independently secured to the side plate below the

fascia, said fascia having a portion over-hanging the upper edge of the sheathing and spaced a slight distance therefrom, permitting the removal of the sheathing independently of the fascia by a combined lateral and vertical movement of the sheathing.

In testimony whereof I affix my signature in presence of two witnesses.

DAVID W. HAWKSWORTH.
